CORPORATION OF CONNECTICUT.

LUNCH-BOX.

1,231,801.

Specification of Letters Patent. Patented July 3, 1917.

Application filed February 23, 1916. Serial No. 79,828.

To all whom it may concern:

Be it known that we, JOSEPH F. SMART and HEMAN C. MAGARGAL, citizens of the United States, and residents of New Britain, 5 in the county of Hartford, State of Connecticut, have invented certain new and useful Improvements in a Lunch-Box, of which the following is a specification.

The object of this invention is to produce 10 a lunch box having certain features of novelty and advantage.

In the drawings—

Figure 1 is a side view of a box embodying our invention with parts of the cover 15 broken away to show construction.

Fig. 2 is a sectional view on the line 2—2 of Fig. 1, looking in the direction of the arrow.

Fig. 3 shows the inside of the top of the 20 cover at one end of the box.

Fig. 4 is an inside end view of the cover at the other end of the box.

Fig. 5 is a side and plan view of an end 25 of the handle.

Referring to the drawings, *a* denotes the base of the box, and *b* the cover which is hinged thereto along one edge as at *c*, which may be described as the back of the box. Upstanding from the front edge of the base 30 are two oppositely arranged catches 2, 2. Inside of the front of the cover there are mounted a pair of spring arms 3, 3, their ends 4, 4, being out-turned and passed through a slot 5 near the edge of the cover, 35 finger pieces being provided at the outer ends. These arms, 3, 3, can spring toward and away from one another, and as the cover is closed the out-turned ends ride down the inclined sides of the upstanding 40 catches 2, 2, until they snap under the projecting lips and interlock therewith, the normal separation of the ends of these arms being such as to cause this interlocking. This provides a very inexpensive and effective means for connecting the front edge of 45 the cover to the base; the two ends must be moved in opposite directions in order to unlock the cover, and this eliminates to a large degree the possibility of the accidental disengagement which would result in spilling the contents of the base, which is the food receptacle.

The novel handle and handle-attaching device, which is inexpensive to manufacture,

readily assembled, and results in a material saving of leather, comprises a pair of retaining members 10, 10, secured to the top of the cover, the sides of which are slotted as at 11, 11, to receive lateral metallic projections 12, 12, from a clip 13 attached to the end of a handle strap 14. The projections 12 can slide back and forth in the slots 11, but are securely held against disengagement with the retaining members 10. The use of the clips 13 reduces the amount of leather required for the handle.

Within the cover there has been provided a novel means for supporting and holding in place a vacuum bottle, the cover itself being shaped and proportioned to receive it. At the inside of one end of the cover there are a pair of spaced projections 20, 20, which receive the bottom of the case of the vacuum receptacle, and retain that end in position. At the opposite end of the case, but spaced from the end wall thereof is a yieldingly supported ring 22, the ends of which are bent at right angles to the plane of the ring and held in a clip 23. This ring is of the proper size to receive the top of the case, and must be sprung out of the way to permit of placing or removing the bottle in the cover. For this purpose it is provided with finger projections 24. To prevent the bottle from shifting lengthwise in the cover, a spring finger 25 is provided, preferably bent down from the metal of the clip 23, and engages the end of the case, forcing it with a slight pressure toward the other end of the cover.

We claim as our invention:

1. In a lunch box, means for suspending a bottle in longitudinal position within the top of said box, comprising a retainer for the bottom of the bottle at one end of the box top, and a ring-shaped support for the top of the bottle spaced from the opposite end of said box and spring-supported from the wall thereof, said ring-shaped support being positioned to normally engage the bottle but movable longitudinally of the bottle out of engaging position with the neck thereof.

2. In a lunch box, means for suspending a bottle in longitudinal position within the top of said box, comprising a retainer for the bottom of the bottle positioned on one end of said box, and a ring-shaped support

- for the top of the bottle resiliently mounted on a wall of the box cover and spaced from the opposite end thereof to normally engage the bottle, said support being movable longitudinally of the bottle out of engaging position with the neck thereof, and means engaging the end of the bottle neck for preventing the longitudinal shifting of the bottle within said box.
- 10 3. A lunch box comprising a food receptacle and a bottle-holding cover, supporting clips near the lower edge of one end of said cover adapted to receive one end of a bottle, a ring resiliently mounted on the inside of said cover between the end walls and adapted to be sprung longitudinally of the cover to permit the placing of a bottle therein, the said ring normally occupying a position embracing the end of the bottle.
- 20 4. A lunch box comprising a food receptacle and a bottle holding cover, supporting clips near the lower edge of one end of said cover adapted to receive one end of a bottle, a ring resiliently mounted on the inside of said cover between the end walls and adapted to be sprung longitudinally of the cover to permit the placing of a bottle therein, the said ring normally occupying a position embracing the end of the bottle, and a resilient clip mounted within said cover adjacent to but spaced from said ring and at the opposite side thereof from the said supporting clip.
- 25 5. A lunch box comprising a food receptacle and a bottle-holding cover, supporting clips at one end of the cover to receive an end of a bottle, a clip secured to a side wall of the cover near its opposite end, and a ring-shaped member provided with lateral arms engaged by said clip and yieldingly supported thereby for movement longitudinally of the bottle.
- 30 6. A lunch box comprising a food receptacle and a bottle-holding cover, supporting clips at one end of the cover to receive an end of a bottle, a clip secured to a side wall of the cover near its opposite end, a ring-shaped member, lateral arms thereon engaged by said clip and providing a yielding support, and a resilient projection from said clip toward the longitudinal center of the cover.
7. In a device of the character described, the combination with a box and its cover, of a retainer at one end of the cover adapted to receive one end of the bottle, and a ring resiliently mounted within the cover near the opposite end thereof and normally adapted to encircle and support the other end of a bottle, said ring being bodily movable longitudinally of the bottle beyond the end thereof and yielding means to prevent longitudinal movement of the bottle.
